W. L. MARDEN

METER

Filed March 5, 1921

Inventor

William L. Marden
By his Attorney
Redding Geely

UNITED STATES PATENT OFFICE.

WILLIAM L. MARDEN, OF NEW YORK, N. Y., ASSIGNOR TO NEPTUNE METER COMPANY,
OF NEW YORK, N. Y., A CORPORATION OF NEW JERSEY.

REEDER.

Application filed March 3, 1921. Serial No. 448,808.

To all whom it may concern:

Be it known that I, WILLIAM L. MARDEN, a citizen of the United States, residing in the borough of Manhattan of the city of New York, in the State of New York, have invented certain new and useful Improvements in Meters, of which the following is a specification, reference being had to the accompanying drawings, forming a part hereof.

In water meters of the general type of that shown in this case, a train of gearing is interposed between the actuator, moved by the flow of water, and the register by which the volume of flow is recorded. The general practise in the construction of such meters, has been so to support the gear train within the meter shell or casing as to permit the water to circulate more or less freely about the gear train and in fact generally to fill that portion of the chamber of the meter in which the gear train is located, the water itself being relied upon as a lubricant for the gear train. It has been demonstrated, however, by practical experience, that the circulation of water in the chamber of the gear train sooner or later washes out whatever other lubricant may have been applied to the gear train and that, in some water, corrosion of the gear train proceeds quite rapidly so that the meter soon ceases to function accurately. Complete exclusion of water from the gear chamber is impracticable. In accordance with the present invention means are provided whereby the circulation of water in the gear chamber is prevented, that is, means whereby the formation of currents of water in the gear chamber is prevented and the washing action of the water is eliminated. In this way a somewhat viscous lubricant applied to the gear train continues to be effective during a long period of time and corrosion is thereby greatly retarded or prevented altogether and long wear attained. The prevention of the circulation of water in the gear chamber is conveniently accomplished by causing the bottom plate, which supports the gear train, to form a water-excluding joint with the meter casing, between the main chamber of the meter, in which is located the driving mechanism, and the gear

chamber. The invention will be more fully explained hereinafter with reference to the accompanying drawing in which—

Figure 1 is a view in vertical section, partly in elevation, of a water meter of well known type to which the invention is applied.

Figure 2 is a partial, similar view, showing a modification to be described.

The meter shown in the drawing is of well known construction, except with respect to the present invention, having a main casing *a*, provided with a water inlet *a'* and a water outlet *a''*, a nutating disc *b*, mounted in a disc chamber *b'* and carrying a driving pin *b''* which engages a star wheel *c* having an upwardly extending shaft *c'*, a reducing gear train *d*, driven by the shaft *c'* and mounted in a frame *d'*, and a register *e* supported in a supplemental casing *f* and driven by gearing *e'*, from the gearing *d*.

Usually, heretofore, the gear train *d* and its frame *d'* have been so supported within the upper part of the casing *a* as to permit the water to circulate more or less freely through the gear chamber and exert a washing action. In the present case the gear train and frame are supported upon a bottom plate *g* which makes with the casing a water-excluding joint, that is, a joint which is permeable but prevents the formation of water currents which would wash off the lubricant from the gear train.

As shown in Figure 1 the bottom plate *g* is centered in the casing by contact with lugs *a''* of the casing and is positioned rotarily by a pin *a'* seated in one of the lugs *a''* and engaging a slot *g'* of the bottom plate *g*. The bottom plate is also provided with a depending and outwardly turned flange *g''* for the purpose of making a water-excluding joint with the casing *a*.

In the embodiment of the invention illustrated in Figure 1 this flange *g''* does not itself contact with the interior of the shell *a*, but supports a flexible, self-sealing gasket *h*, which is held in place by the pressure against its under side. The construction shown in Figure 2 is the same as that shown in Figure 1 except that the depending and out-turned flange *g''* is machined at its outer edge to fit rather snugly within the casing as indicated at *a''*.

2 Before the gearing is put in place it is coated with a suitable adhering lubricant, preferably somewhat viscous and heavy, and it has been found that such lubricant, when protected in the manner described against the wash of water currents, continues to be effective for a very long time.

I claim as my invention:

1. In a meter, the combination of an integral casing having a top plate and forming a disc chamber with water inlet and water outlet, a gear train, a frame suspended from said top plate and supporting the gear train in the casing, and a bottom plate imperforate except for a shaft opening formed with a depending and out-turned flange which forms with the casing a joint which is permeable but not sufficient to permit the formation of

mit the formation of washing currents of water about the gear train.

2. In a meter the combination of an integral casing having a top plate and forming a disc chamber with water inlet and water outlet, a gear train, a frame suspended from said top plate and supporting the gear train in the casing, a bottom plate imperforate except for a shaft opening secured to said frame and having a depending and out-turned flange, and a gasket supported by the out-turned flange and forming with the casing a joint which is permeable but not sufficient to permit the formation of washing currents about the gear train.
